CLAIM

The ornamental design for a street clock, as shown and described.

DESCRIPTION

FIG. 1—is a right front perspective view of a street clock showing our new design;

FIG. 2—is a front elevational view thereof;

FIG. 3—is a rear elevational view thereof;

FIG. 4—is a bottom plan view thereof;

FIG. 5—is a top plan view thereof;

FIG. 6—is a right side elevational view thereof; and,

FIG. 7—is a left side elevational view thereof.

The broken lines shown in FIG. 4 represent a boundary, the area within which forms no part of the claimed design.

1 Claim, 5 Drawing Sheets
